RADIO CABINET AND SHOCKMOUNT BASE

Henry T. Winchel, North Hollywood, Calif., assignor, by mesne assignments, to Bendix Aviation Corporation, South Bend, Ind., a corporation of Delaware

Application April 5, 1943, Serial No. 481,899

4 Claims. (Cl. 174—51)

1

This invention relates to radio cabinets, and more particularly to a combined shockmount and radio cabinet, suitable for fabrication from sheet metal.

It is an object of the invention to provide a cabinet and shockmount having a novel mounting base which permits rapid installation and removal of the radio cabinet.

Another object is to provide a mounting base for a radio cabinet permitting the locking of the cabinet to the mounting base by a single turn of a thumbscrew.

Still another object is to provide a cabinet cover, which is secured to its base by the combination of a pair of fixed pin fitting holes and a single screw.

A further object is to provide a cabinet construction wherein the cover meets the base with a flush contact.

Other objects and advantages of the invention will be apparent in the following description and claims.

In the drawing forming a part of this specification:

Figure 1 is an elevation view in full section of the cabinet and shockmount of this invention.

Figure 2 is a sectional view of the cabinet along the lines 2—2 of Figure 1; and

Figure 3 is a fragmentary sectional view of the cabinet along the line 3—3 of Figure 1.

Referring to Figure 1, a sheet metal mounting base 10 of open top box shape may be secured to any desired structure; for example, the frame of an airplane when the radio is for airplane use. Two tapered pins 12 are secured to the left or rear wall of mounting base 10, as by spinning or riveting, and projecting inwardly. Fastened to the right or forward wall of mounting base 10 is a length of spring wire 14 placed over a hole 16 in that wall.

Adapted to be placed upon mounting base 10 is a shockmount base 18, of inverted open box construction. The left or rear wall of this base fits inside of mounting base 10, but the other three walls fit outside mounting base 10. Holes 20 in the left or rear wall fit over pins 12 to hold the shockmount base 18 to mounting base 10. On the right wall of shockmount base 18 is a thumbscrew 22 having a spirally slotted shank such as to receive spring wire 14 and lock upon that wire when rotated, as well known in the art. Thumbscrew 22 is oppositely rotated to release wire 14, and thereafter the cover 18 may be moved forwardly, or to the right, to be released from pins 12. Shockmounts 24 are secured to

2

base 18 and the forward mounts are grounded by a jumper 26. Inasmuch as jumper 26 and shockmounts 24 may catch on the forward or right wall of mounting base 10, a guide 28 is provided which will be contacted by the mounting base, leaving jumpers 26 uninjured.

Secured to shockmounts 24 by screws 30 is a dished cabinet base 32. Screws 34 are threaded into hexagonal spacing posts 37 spun onto a chassis 35 to hold the radio chassis 35 to base 32. Holes 36 are provided in mounting base 18 to permit access to and removal of the screws 34, so that the chassis 35 may be removed for any desired purpose. Chassis 35 has two stub pins 46 spun thereon. Cabinet base 32 has a right or forward wall 38 terminating in an angle member 40. Secured to angle 40 is a spring wire 42 passing over a hole 44.

Placed over chassis 35 is a cabinet cover 48 having holes 50 in the rear or left wall which fit over pins 46. Cover 48 makes a close contact with dished base 32 and the construction results in a flush contact of cover 48, with the base 32. The right or forward end of cabinet cover 48 is held down by a screw 52 having a spiral slot which permits it to lock upon spring wire 42.

The construction of the forward or right end of the cabinet is shown in Figure 3. There it will be noted that the edges of front plate 39 are backed by strips 39, permitting the edges of cover 48 to lie flush with the major portion of face 38. A handle 56 is fastened to cover 48 so that the entire cabinet and shockmount base 35 may be carried about as a unit.

In operation, the cabinet 48 and 32 and shockmount base 18 may be removed from mounting base 10 by rotating thumbscrew 22 until it releases wire 14. Handle 56 is then grasped and 40 the set moved manually forward until pins 12 are released, after which the unit is free of mounting base 10. During this operation guide 28 may contact the right wall of mounting base 10 preventing injury to jumper 26.

If it is desired to remove cover 48, a screw driver is used to rotate screw 52 to unlock wire 42 from screw 52 and the cover 48 is rotated about pins 46 until the right corners of chassis 35 are cleared. Then the cover 48 is moved to 50 the left releasing it from pins 46, whereupon it is free to be removed. If it is desired to remove the chassis, screws 34 are removed, allowing the chassis to come free of all other structural parts.

Although the invention has been described with reference to a particular embodiment thereof,

it is not intended to limit the invention to this embodiment, or to the description, or otherwise except by the terms of the following claims.

I claim:

1. A radio cabinet mounting comprising a shockmount base in combination with a mounting base, said mounting base including inwardly projecting pins, and means to which a screw may be fastened, said shockmount base comprising a downwardly projecting surface having holes therein to match said pins, and screw means to engage said screw fastening means.

2. A mounting base for use with a shockmount base having downwardly-extending side walls at opposite edges, one of which side walls has holes therein, and the other of which has a screw-type securing means, said mounting base comprising a shallow, open-top box having one upwardly-extending side wall with pins projecting inwardly for engaging the holes in the one side wall of the shockmount base and having an opposite upwardly-extending wall containing means for engagement by said screw-type securing means of the shockmount base.

3. A shockmount base adapted to be secured to a mounting base having opposite upwardly-extending side walls, one of which contains inwardly-extending pins, and the other of which contains means for engagement by screw-type securing means; said shockmount base comprising a plate having downwardly extending side walls at opposite edges, one of which side walls has holes therein adapted to engage said pins of the mounting base when positioned within the wall containing said pins, and the other of which side walls is adapted to rest against the

outer surface of the other side wall of the mounting base and includes screw-type securing means for detachably securing said last-mentioned walls together, whereby said shockmount base is removable from said mounting base following disengagement of said securing means by sliding movement to disengage said holes from said pins, said shockmount base having shockmounts secured thereto and extending therebelow, a grounding jumper connecting at least one of said shockmounts to said plate and extending therebelow, and a shielding member extending over said jumper to protect it from injury during movement of said shockmount base to detach it from said mounting base.

4. A radio cabinet mounting having on the under side thereof a shockmount base having downwardly-projecting side walls at opposite edges thereof, a mounting base including a floor member having upwardly extending walls at opposite edges thereof, one of which is adapted to be positioned exterior of one of said downwardly projecting walls on the shockmount base, and having pins projecting inwardly therefrom, holes in said one downwardly-extending wall for engagement by said pins, the other downwardly-extending wall of said shockmount base being adapted to rest against the outer surface of the other upwardly-extending wall of the mounting base, and screw-type securing means on said other downwardly-extending wall, and means for engagement by said screw-type securing means on said other upwardly-extending wall for securing said other walls together.

HENRY T. WINCHEL.
